(74) *Attorney, Agent, or Firm* — Michael Best & Friedrich LLP

(57) **CLAIM**

The ornamental design for a blade, as shown and described.

DESCRIPTION

FIG. 1 is a top perspective view of a blade.

FIG. 2 is a bottom perspective view of the blade shown in FIG. 1.

FIG. 3 is a top view of the blade shown in FIG. 1.

FIG. 4 is a bottom view of the blade shown in FIG. 1.

FIG. 5 is a left side view of the blade shown in FIG. 1.

FIG. 6 is a right side view of the blade shown in FIG. 1.

FIG. 7 is a front view of the blade shown in FIG. 1.

FIG. 8 is a rear view of the blade shown in FIG. 1.

FIG. 9 is a top perspective view of a blade.

FIG. 10 is a bottom perspective view of the blade shown in FIG. 9.

FIG. 11 is a top view of the blade shown in FIG. 9.

FIG. 12 is a bottom view of the blade shown in FIG. 9.

FIG. 13 is a left side view of the blade shown in FIG. 9.

FIG. 14 is a right side view of the blade shown in FIG. 9.

FIG. 15 is a front view of the blade shown in FIG. 9; and,

FIG. 16 is a rear view of the blade shown in FIG. 9.

The dash-dash broken lines represent portions of the article that form no part of the claimed design. The dash-dot broken lines represent boundaries of the claimed design and form no part of the claimed design. Stippling and straight-line surface shading are used to show surface contrast. In FIGS. 1-16, the article is a blade, such as an oscillating multi-tool or the like.

1 Claim, 12 Drawing Sheets
